UNITED STATES PATENT OFFICE

ROBERT S. TURNER, OF INDIANAPOLIS, INDIANA

POWER WHEEL

Application filed July 31, 1930. Serial No. 472,065.

This invention relates to power wheels of that class adapted to be operated by either air or running water and the prime feature of this invention is the provision of propelling blades arranged in companion pairs with one of the blades of each pair arranged to turn broad side to the air or stream of water to receive driving power and the other blade of the same pair turn edgewise to the blast of air or stream of water so as to present the least resistance.

A further feature of the invention is the provision of means for mounting the pairs of blades whereby the force of the air or stream of water will automatically change the positions of the blades.

A further feature of the invention is in so constructing the wheel structure that any suitable number of the pairs of blades may be incorporated into a single unit.

A further feature of the invention is the provision of means for maintaining the power structure edgewise to the wind current.

A further feature of the invention is in so mounting the power wheels, that any suitable number of the wheels may be employed for driving a single element.

Other objects and advantages will be hereinafter more fully set forth and pointed out in the accompanying specification.

In the accompanying drawings which are made a part of this application,

Figure 1 is a side elevation of a set of power wheels showing one manner of applying the same to use.

Figure 2 is an enlarged detail edge elevation of one of the power wheels applied to use.

Figure 3 is an enlarged face elevation of the hub structure of one of the power wheels, and,

Figure 4 is a sectional view therethrough as seen along line 4—4, Fig. 3.

Referring to the drawings in which similar reference numerals designate corresponding parts throughout the several views, the numeral 1 designates a tower structure, such as is commonly used for elevating air operated power wheels a distance above the ground surface so as to obtain a better and more direct air current.

Rotatably mounted at the upper end of the tower structure 1 is a housing 2, into which extends a driving shaft 3, said housing being pivotally mounted so that it may be readily rotated to keep the power wheels 4 into the wind. The power wheels 4 are mounted on shafts 5, which are preferably at right angles to the main driving shaft 3 and when two of the shafts 5 are incorporated with the main driving shaft 3, any suitable differential gear mechanism (not shown) is mounted in the dome portion 6, of the housing 2 and adapted to cooperate with and drive the shaft 3, when the power wheels are driven.

Each power wheel comprises a hub 7, to which are attached any suitable number of spaced discs 8 and to said discs are pivotally or hingedly attached cross arms 9, preferably of angle iron, although any suitable material may be used preferably by means of hinges 10 which are so attached to the disc and arm that the arms may have oscillatory movement, one angle of the arm limiting the swinging action of the arm in one direction, while the other angle limits the swinging action of the arm in the opposite direction.

Attached to the ends of the cross arms 9 are blades 11, one of which is substantially in line with one angle member of the cross arm and the other blade in line with the opposed angle member of the arm so that the flat faces of the blades will be approximately at right angles to each other, whereby, when one of the blades is turned broad side to the air or water current for receiving the force of such current, the opposite blade will be turned edgewise to such current so that the latter blade will move through the air or water without setting up any material resistance.

As previously stated, any suitable number of the discs 8 may be incorporated into a single hub portion, but in the present instance a pair of the discs are shown with each hub portion, with a cross arm 9 attached to each disc, one cross arm being at a phase difference of substantially one-half the diameter of the disc from the other arm. Associated with the housing 2 is a vane or rudder 12, which serves to constantly maintain the

power wheel in position to receive the force of the air current, said vane maintaining the power wheel 4 edge wise to the air current, when operated by air.

5 When the power wheel is driven by a current of water, the wheel is so located that the blades will position horizontally with respect to the surface of the body of water, the operation of the blades 11 being the same as when operated by air currents.

10 Owing to the fact that any number of power wheels may be attached to a single shaft, the power creating proficiency thereof is greatly enhanced and as all resistance is 15 eliminated from the blades on their return stroke, the power wheel may be efficiently operated with a lighter air or water current.

15 It will likewise be seen that owing to the great simplicity of this device it may be constructed at a minimum expense and with but 20 few wearing parts so that the life of the device will be unlimited.

What I claim is:

25 1. In a power wheel, a hub structure comprising a plurality of spaced discs, a cross arm hinged to each disc and with its ends extending a distance beyond the peripheral edge of the disc and adapted to swing to different positions, each cross arm having flat faces 30 adapted to limit the hinging movement of said arm by contacting with the face of the disc, a blade at each end of each cross arm, the blade at one end of each cross arm being at right angles to the blade at the opposite end 35 thereof, whereby when one flat face of the cross arm is in engagement with the face of the disc one of the blades of each cross arm will be faced flatwise to the propelling current and the other edgewise thereto.

40 2. In a power wheel, a hub structure comprising a rotatably mounted disc, a cross arm having flat faces and having its ends projecting a distance beyond the peripheral edges of the disc, a hinge connecting said 45 arm to the face of said disc in a manner to cause the flat faces of the arm to limit the hinging action of said arm by contacting with the face of the disc, and a blade at each end of said arm, said blades being arranged at right 50 angles to each other, whereby when one of said blades is faced flatwise to the propelling current the other blade will be edgewise thereto.

55 3. In a power wheel, a hub structure comprising a flat faced disc, a cross arm right angular in cross section, a hinge for connecting said arm to the face of said disc in a manner to cause the flat faces of said arm to engage the face of the disc and limit the hinging movement of said arm, and a blade along 60 each end portion of said arm one of which will rest edgewise to the propelling current when the other is faced flatwise to the current.

65 4. In a power wheel, a hub structure comprising a plurality of spaced discs, a cross arm for each disc right angular in cross section,

a hinge connecting each cross arm to each disc so that the flat faces of the arms will engage the face of the discs and limit the hinging action of said arms, and a blade at each end of each cross arm and beyond the confines of said discs, one of which will rest edgewise to the propelling current when the other blade is flatwise thereto.

70 In testimony whereof, I have hereunto set my hand.

ROBERT S. TURNER.
